Attorney

UNITED STATES PATENT OFFICE.

LOUIS W. JONES, OF CLEVELAND, OHIO.

PIPE-BENDING DEVICE.

1,378,796.

Patented May 17, 1921.

Application filed February 14, 1920. Serial No. 358,658.

To all whom it may concern:

Be it known that I, LOUIS W. JONES, a citizen of the United States, residing at Cleveland, in the county of Cuyahoga and 5 State of Ohio, have invented certain new and useful Improvements in Pipe-Bending Devices, of which the following is a specification.

My invention relates to a device to be used 10 in bending pipe, being particularly intended to be used by workmen installing electric systems where pipes are used to carry the conducting wires, which pipes, being supplied in straight pieces of stock length, are 15 bent and cut to suit the requirements of each particular job. The invention, however, is not limited in its useful application to such use.

Referring to the drawings—

20 Figure 1 is a plan view of one form of the invention.

Fig. 2 is a sectional view taken on the broken line II—II of Fig. 1.

Fig. 3 is a detached perspective view of 25 one of the bending blocks constituting part of the device shown in Fig. 1.

Fig. 4 is a plan view of a device somewhat different from that illustrated in Fig. 1.

Fig. 5 is a sectional view on the line V—V 30 of Fig. 4.

Fig. 6 is a plan view of still another embodiment of the invention.

Referring particularly to the form of device illustrated in Figs. 1 and 2, 2 indicates 35 the base of the device, being a casting of the desired shape, such as illustrated in the drawings, and adapted to be secured to a suitable support, as by screw bolts adapted to pass through the holes 3. At one end 40 of this base plate is secured a pipe vise 4. This may be of any usual or preferred kind or construction. That shown in Figs. 1 and 2 is represented as having its upper part, carrying the adjustable clamping jaw 6, 45 pivotally connected with the base piece at 5, the latter being shaped to receive the stationary clamping jaws 7. This arrangement permits the pivoted part to be thrown back to admit the piece of pipe A that is to be bent. 8 represents a pivoted hook connected 50 with the upper swinging portion of the pipe vise and adapted to engage with a lug 9 on the base plate. There are two of these lugs 9 on opposite sides of the device, and 55 also two perforated stationary bearings 22 for the pivot bolt 5, permitting the pipe

vise to be reversibly supported so that its upper part may be swung either to the right or to the left as desired.

10 designates a bending block. It preferably has two faces at right angles to each other, these being united by a curved face that constitutes the die against which the pipe is bent and which determines the radius of the bend that shall be imparted thereto. The bending block 10 is held in place upon the surface of the base piece 2 and in front of the pipe vise 4 by a strong bolt 11 seated in a screw threaded aperture provided therefor in the plate. 70

One of the straight edges or faces of the block 10 bears against an abutment ledge 12 located between the bolt 11 and the pipe vise. This ledge which is preferably an integral part of the casting 2 serves to relieve 75 the bolt 11 of strain during the pipe bending operation.

13, 14 indicate a series of parallel straight low ridges integral with the base piece 2 and located at one of the sides thereof and near the toe 23 of the block or former 10 being used. They are shown as disposed at right angles to the line of the pipe A when secured in the vise. They serve to assist the operator in determining when the pipe has 80 been bent to such extent that its straight portions are at right angles to each other. There may be several of these ridges as shown, and they may be duplicated on the opposite sides of the base plate, and may 85 be arranged at different angles relative to the line of the pipe when held in the vise from that shown, if desired.

The device is provided with several bending blocks to be used in making bends of 90 larger or smaller radius, as may be desired. The apparatus shown in Fig. 1 carries three blocks, 10, 10', 10'', the one designated 10 being in position for use, and those designated 10', 10'' supported on the opposite side 100 of the plate from the bending block 10, so as to be out of the way when bending block 10 is being used, and yet in convenient position to be substituted for block 10 if occasion requires. Indeed block designated 10' could 105 be used when supported as shown if it were desired to make what is known as a left hand bend. Most workmen prefer to use a pipe bending device the other way, bending the pipe in the direction indicated by the 110 dotted lines in Fig. 1, and therefore it will be common practice to substitute one bend-

ing block for another, the one used being usually in the position indicated by the block 10 in Fig. 1. The heel 24 of each bending block, that is, the portion with 5 which the pipe first engages, and being the part of the curved bending face of the former nearest to the pipe vise when in position for use, is at such distance from the axial center of the securing bolt that such 10 heel is on the line occupied by the edge of the pipe to be bent when clamped in the vise. Since there is a common securing and holding means for the several blocks or formers, the distance of the heel 24 from the 15 aperture through which passes the securing bolt will be a little different in one former from what it is in another. Thus in former 10' which is properly shaped for giving the desired bend to one inch pipe, such distance 20 will be a little less than in former 10, which is shaped for use when three-quarters inch pipe is to be bent; while the distance of the heel from the bolt opening in former 10'', used in bending one-half inch pipe is a little 25 greater than the distance in former 10. This expedient makes it unnecessary to change the position of the vise whenever the bending block or former is changed.

The reserve bending blocks are held in 30 place upon the face of the base by bolts 14, 14'.

15 represents a roller supported by bracket 16 at the end of the base piece 2 opposite the pipe vise. This serves as a rolling support for the pipe A when being introduced 35 into the vise. It also serves as a convenient handle by which the device may be carried.

When using a device such as described it becomes a very simple matter to accurately 40 determine the distance from the end of the pipe to the bend which is made by the use of one of the formers. For instance, the block 10 is of such size that the distance from the outer edge of the right angle bend given to a pipe of say one-half inch diameter to the outer faces of the clamping jaws 45 of the pipe vise, is six inches. If, therefore, it is desired that the bend in the pipe shall be four feet, six inches from the end of the pipe, it is only necessary that the 50 pipe be extended exactly four feet beyond the outer face of the clamping jaws. This measurement having been made and the pipe secured by the vise, the pipe is bent and the bend is formed at exactly the desired distance from the end of the pipe.

The form of invention shown in Figs. 1 and 2 contemplates the base piece being especially constructed to support a vise of the form shown, parts of which are integral 60 with the casting 2. In Figs. 4 and 5 I have shown a form of the invention with which an ordinary pipe vise separable from the casting 2 may be used. Here the base piece or casting is formed with a platform or 65 projection 17 adapted to support and have

bolted to it the pipe vise, the position of the base of which is designated by the dotted lines in Fig. 4.

In Fig. 6 I have shown a form of the invention in which the bending pieces are 70 different from those shown in the other views. Here they are represented as formed of a series of concentric cylinders 18 supported upon bolts 11. There are several of these cylinders. When they are all in place 75 as represented in Fig. 6, a bend of large radius is given to the pipe. If a bend of smaller radius were desired one or more of the cylinders would be removed, the remaining ones serving as the bending die. 80

In this form of the invention it is necessary that the pipe vise be adjustable in order to bring the clamping jaws thereof in proper relation to the face of the particular cylinder 18 that may be selected to serve as the bending piece or die. I secure this adjustment by pivotally supporting the vise, as indicated at 19, permitting it to be turned so that the edge of the pipe will just contact with the edge of the cylinder 18 that 90 is to be used as the former.

The several cylinders 18 nest together quite closely, but may be separate as occasion may require. To hold them in place I may use a crosspiece adapted to lie over the ends of the several cylindrical pieces 18, and held in place by the bolt 11, or else, and preferably, provide each inner cylinder with projections 23 that rest in recesses provided therefor in the ends of the cylinder 100 next larger. Thus the projections on each smaller and inner cylinder holds in place each larger and outer cylinder when they are concentrically arranged and the bolt 11 is in place, as represented in Fig. 6. 105

The upper face of the ledge 12 is preferably in the same horizontal plane as is the upper edge of the roller 15, so that the pipe when in proper position to be clamped by the vise rests upon the upper faces of the 110 ledge 12 and the roller 15.

In that form of the invention represented in Fig. 6 the ledge 12 serves primarily as a support for the pipe.

What I claim is:—

1. In a pipe bending device, the combination of a base, a pipe vise supported at one end of the base, an abutment ridge rising from the base in front of the vise, a removable bending former adapted to rest upon the base and having one face adapted to bear against the said abutment ridge, and another face curved with a heel in line with the pipe to be bent when held in the vise, and means for securing the former to the 120 base in the position stated.

2. A pipe bending device, comprising a base plate, a pipe vise supported by the plate, a plurality of bending blocks of different radii, means for securing the said 130

blocks upon the face of the plate, two of the blocks being on opposite sides of the line of a pipe held in the vise and in position for either one to act as the bending die for 5 a piece of pipe so held and a transverse abutment ridge located between the bending blocks and the pipe vise against which rest the side edges of the bending blocks when in position for use.

10 3. A pipe bending device, comprising a base plate, a plurality of bending blocks of

different radii, means for securing these upon the face of the plate with one at least in position for use, a vise for holding the pipe to be bent located at one end of the 15 plate, and a roller supported at the end of the plate opposite the vise arranged to serve as a support for the pipe about to be bent, and also as a handle by which the device may be carried.

LOUIS W. JONES.
